UNITED STATES PATENT OFFICE.

ERHARD ALLEN, OF DAYTON, OHIO, ASSIGNOR TO THE DAYTON DISPLAY FIXTURE COMPANY, OF DAYTON, OHIO, A CORPORATION OF OHIO.

DISPLAY RACK.

1,411,554.

Specification of Letters Patent.

Patented Apr. 4, 1922.

Application filed July 16, 1921. Serial No. 485,183.

To all whom it may concern:

Be known that I, ERHARD ALLEN, a citizen of the United States, residing at Dayton, in the county of Montgomery and State of Ohio, have invented certain new and useful 5 Improvements in Display Racks, of which the following is a specification.

The principal object of my invention is to provide a display rack that may be readily 10 taken apart for shipment in a small space, and thereafter readily assembled by the user.

Other important and incidental objects will be brought out in the following specification and particularly set forth in the subjoined claims.

In the accompanying drawings, Figure 1 is a front view of the display rack, the right half being in assembly and the left half 20 showing the means for attaching the braces to the upright members. Figure 2 is an end view of the assembled rack, showing one tray in place. Figure 3 is a detail end view, showing a tray on one side in place. 25 Figure 4 is a plan view of the same. Figure 5 is a bottom plan view of a tray, showing how the cross strips are riveted thereto. Figure 6 is a cross section taken on the line 30 6-6 of Figure 4, showing the brace and wing nut construction. Figure 7 is an end view of one bottom side of the rack, showing the means for holding the entire frame in alinement after the cross braces are fastened to the upright members by the wing 35 nuts. And Figure 8 is a top plan view thereof.

Throughout the specification and drawings similar reference characters denote corresponding parts.

40 Referring to the accompanying drawings, the numerals 1, 1 designate two runners respectively, each of which is supported by two rollers 2, 2. Each runner is constructed of two angle irons between the ends of whose 45 upturned flanges are bolted the ends of an arch-shaped supporting member 3. Provided in the front top portion of each arch shaped member 3, are two hook-shaped notches 4, 4, while in the rear top portion 50 of each arch shaped member 3 are two hook-shaped notches 5, 5 that are inclined in the opposite direction. (See Figures 2 and 7).

55 Adapted to be supported upon each side of the display rack, by the notched arch shaped members 3, 3, is a combined box and basket holder 6. The latter preferably com-

prises a rectangular frame divided into box and basket receiving spaces by pairs of transverse members 7, 7 connected between the longitudinal side members 8, 8 of said frame. The transverse members 7, 7 that fit over the arch shaped members 3, 3 are disposed a sufficient distance apart by spacers 9, 9 to straddle said arch shaped members. Referring to Figure 8, each 65 spacer is a cylindrical piece of metal that is turned down at its middle part to enter a notch provided to receive it in an arch shaped member 3. Accordingly, when it is desired, for example, to mount one of the 70 combination box and basket holders upon the front portion of the rack, the holder is brought to a position to permit the reduced middle portions of its spacers 9, 9 to enter the notches 4, 4 respectively in each 75 arch shaped member 3, by which it will be supported in an inclined position, as shown in Figure 4.

When the combination box and basket 80 holders are secured as above described, upon the arch shaped members 3, 3, they serve to hold the latter in alinement. When it is desired to remove the box and basket holders to conserve space in shipping the display rack, it is only necessary to withdraw 85 the reduced middle portions of the spacers 9, 9 from the notches that receive them in the arch shaped members 3, whereupon the holder may be easily lifted from the rack.

Straddling the middle portions of the upturned flanges of the angle irons forming each runner 1, are the lower ends of a pair of vertically disposed channel members 10, 10. A short distance above each arch shaped 90 member 3, there is connected between each 95 pair of channel members 10, 10, by a long bolt 11, a pair of transverse bars 12, 12, whose outer ends incline downwardly as shown in Figures 2 and 3. Connected between the outer ends of the bars 12, 12, by 100 bolts 13, are the ends of a bar 14 that incline downwardly from said bolts to a bolt 15 by which the middle portion of said bar 14 is secured between the channel members 10, 10. (See Figures 3, 4 and 6).

105 A tray 16 is adapted to be supported upon the inclined portions of the bars 12 on each side of the channel members 10, the bars 14 acting as braces for the bars 12 to assist them in supporting the weight of the trays. (See Figure 3).

For the purpose of firmly holding a tray

16 upon the bars 12, there are riveted to the bottom 17 of each tray 16 two pairs of cross strips 18, 18 having downwardly turned outer ends 19. The cross strips 18, 18 of 5 each pair are spaced a sufficient distance apart, and they are so located on the bottom 17 of a tray 16, as to straddle the inclined portions of the bars 12 when the tray is set upon them as shown in Figure 3.

10 When mounted on said bars, the downwardly turned ends 19 of the cross strips 18 will bear against transverse locking pins 20 in the outer ends of the bars 12 to prevent the tray from slipping off the rack. (See 15 Figures 3 and 4). The tray may be easily lifted from the bars 12 to conserve space in shipping the display rack, and may be readily replaced thereon when the rack is assembled by the user.

20 For the purpose of bracing the two pairs of channel members 10, 10, that they may be maintained in vertical alinement when the rack is assembled, the following means are provided. Referring to Figures 1 and 6, 25 the numerals 21, 21 designate two bracing members that are connected at their middle portions in scissor fashion by a pivot pin 22. Each bracing member 21 has ends 23, 23 that are turned in the same direction as 30 the channel members 10, 10. Through holes in these ends the long threaded ends of the bolts 11, and the long threaded ends of similar bolts 11 in the channel members 10, 10 below the first bolts 11, are adapted to 35 pass. Against nuts 24 which, with the heads of the bolts 11, the channel members 10, 10 are firmly held together, the ends 23 of the bracing members 21 are adapted to be tightly pressed by wing nuts 25 or 40 other suitable fastening elements on said bolts. When the ends 23 of the bracing members 21 are so connected to the channel members 10, 10, they firmly maintain the two pairs of the latter in alinement. By 45 removing the wing nuts 25, the bracing members 21, 21 may be easily disconnected from the channel members 10, 10 to conserve space in the shipment of the display rack.

50 Upon bars 12 secured to the channel members 10 above the first bars 12, trays 26 are mounted similarly to the trays 16. (See Figures 1 and 2). Any number of trays may be so mounted upon the display rack.

55 When it is desired to ship the display rack, the trays are lifted from the bars 12 in the manner hereinbefore described, after which the box and basket holders 1 are removed and the bracing members 21, 21 detached from the channel members 10. The various detached members of the display rack may now be placed together for shipment in less than half the space that would be occupied by the rack in its assembled 60 state. Upon its arrival at destination, the

user may readily assemble it in a short time. I do not wish to be limited to the details of construction and arrangement herein shown and described, and any changes or modifications may be made therein within 70 the scope of the subjoined claims.

Having described my invention, I claim:

1. In a display rack, the combination with a pair of horizontal base members, of a standard projecting upwardly from each base member, a horizontal bar secured to each standard, a receptacle mounted on said bars on each side of the standards, a transverse locking element carried by the outer end of each horizontal bar, and means on 80 the bottom of said receptacle adapted to fit over said horizontal bars between the standards and the locking elements, for the purpose specified.

2. In a display rack, the combination with a pair of horizontal base members, of a standard projecting upwardly from each base member, a horizontal bar secured to each standard, a receptacle mounted on said bars on each side of said standards, a transverse pin carried by the outer end of each horizontal bar, a pair of cross pieces secured to the bottom of said receptacle, to straddle a respective horizontal bar, and turned-down outer ends on said cross pieces adapted to engage said transverse pins, for the purpose specified.

3. In a display rack, the combination with a pair of horizontal base members, of a standard projecting upwardly from each base member, a horizontal bar secured to each standard, a receptacle mounted on said bars on each side of said standards, a box holder removably connected between the lower ends of said standards, and removable bracing members removably connected between the side portions of said standards to co-operate with the box holder in maintaining said standards in alinement.

4. In a display rack, the combination with a pair of horizontal base members, of a pair of channel members projecting upwardly from each base member, a horizontal bar disposed between said channel members, a bolt having an elongated threaded end passing through said channel members and the horizontal bar, a receptacle mounted on said bars on each side of said standards, a bracing member through a hole in one end of which the threaded end of said bolt projects, and a threaded element adapted to press the end of said bracing member toward the channel members, for the purpose specified.

In testimony whereof I have hereunto set 125 my hand this 14th day of July, 1921.

ERHARD ALLEN.
HOWARD S. SMITH.
